ELECTRICAL CONTACT MEANS

Original Filed Aug. 23, 1935

UNITED STATES PATENT OFFICE

2,234,820

ELECTRICAL CONTACT MEANS

Harry A. Douglas, Bronson, Mich., assignor to
Kingston Products Corporation, a corporation
of Indiana

Original application August 23, 1935, Serial No.
37,489. Divided and this application June 24,
1938, Serial No. 215,520

6 Claims. (Cl. 173—328)

My invention relates to electrical connection means, and more particularly to means for receiving conductor terminals of the snap type, and the principal object of my invention is to provide new and improved electrical connection means for these types.

This application is a division of my copending application Serial Number 37,489, filed August 23, 1935.

10 In the drawing accompanying this specification and forming a part of this application, I have shown, for purposes of illustration, various forms which my invention may assume, and in this drawing:

15 Figure 1 is an elevation of one embodiment of my invention,

Figure 2 is a section taken on the line 2—2 of Figure 1, looking in the direction of the arrows and including, in addition, a plug conductor terminal adapted to cooperate therewith,

20 Figure 3 is a perspective view of the parts comprising the embodiment shown in Figure 1, the parts being shown in disassembled relation,

25 Figure 4 is an elevation of a different embodiment of my invention,

Figure 5 is a section taken on the line 5—5 of Figure 4, looking in the direction of the arrows, and

30 Figure 6 is a perspective view of the parts comprising the embodiment shown in Figure 4, the parts being shown in disassembled relation.

Referring to the embodiment of my invention shown in Figures 1, 2, and 3, a terminal post 10 is suitably mounted on a base 11. The terminal post 10 includes a body 12, here shown as made of sheet metal stock, bent in a right angular formation as viewed in Figures 2 and 3. The body 12 includes a vertical generally rectangular plane wall 13, and a horizontal plane wall 14, the latter wall serving as a foot for the body 12, and being integral with the vertical wall 13 and extending at right angles therefrom at the lower end thereof.

The terminal post 10 is provided with a plug 45 terminal receiving recess, including an arcuate aperture 15 adjacent the top margin of the wall 13. The vertical wall 13 is further formed with a generally diagonally disposed slot 16 extending from the junction of the walls 13 and 14 to and 50 intersecting the aperture 15. The slot 16 comprises a marginal wall 17, substantially straight in extent, and an opposite marginal wall 18 having its lower part parallel with the wall 17, and intermediate its extent diverging from parallelism 55 with the wall 17, as shown at 19, and terminating

in an angularly disposed marginal wall 20 intersecting the aperture 15.

The vertical wall 13 is provided with a slot 21, spaced from and to the left of the lower end of the slot 16 as viewed in Figure 1, and the slot 21 extends into the horizontal wall 14 and communicates with a transverse slot 22 which in turn communicates with the slot 16. The slots 16 and 21 define between them a toe 23 forming a continuation of the vertical wall 13 and extending 10 to the plane including the lower surface of the horizontal wall 14. The horizontal wall 14 is provided with an aperture 24, spaced from the vertical wall 13, and adapted for the reception of a suitable fastening means, here shown to be a 15 screw 25 passing through the aperture 24 and having its screw-threaded end engageable with a screw-threaded aperture 26 formed in the base 11. The horizontal wall 14 may be provided with a lug (not shown) extending into a recess or aperture 20 in the base 11 to prevent turning of the terminal post 10 about the fastening means 25.

In manufacture, the body 12 may be formed from an elongated strip of metal, and the desired lengths of the walls 13 and 14 may be formed 25 therefrom, and the aperture 15, slots 16, 21, and 22, and aperture 24, may be formed therein in any suitable manner, as by stamping or punching, and the body then bent to the desired right angular formation.

30 Biasing means 27 are provided for cooperation with the body 12, and comprise a generally plane leaf-spring like member 28, adapted to be disposed in the slot 16, but being of a greater width than the thickness of the wall 13, so that when 35 the member 28 is in position with respect to the slot 16, portions thereof will be disposed on opposite sides of the wall 13. The member 28 is provided at its upper end, as viewed in Figures 1 and 2, with a slot 29, preferably of a width to 40 freely pass the thickness of the wall 13, the slot 29 forming longitudinally extending fingers 30. The opposite end of the member 28 is angularly bent, as shown at 31, and the bent portion 31 is provided with a slot 32 preferably of the same width 45 as the slot 29, the slot 32 forming longitudinally extending fingers 33.

To assemble the terminal post 10, the part of the spring member 28 carrying the fingers 30 is inserted in the slot 16, and inserting movement 50 is continued until a margin 34 of the slot 29 abuts the marginal wall 20 of the slot 16. In this position the fingers 30 formed by the slot 29 will overlap adjacent portions of the wall 13, and the angularly bent portion 31 of the member 28 will have 55

its lower surface flush with the lower surface of the horizontal wall 44, with the fingers 33 thereof straddling the toe 23. The body 12 is then fastened to the base 11 by means of the screw 25 and the parts are securely assembled by reason of the fact that both the body 12 and spring member 28 are held to the base 11.

As shown in Figure 1, the spring member 28 normally assumes a straight diagonal position 10 intersecting and forming a chord across the arcuate aperture 15, and at its lower part, closely fitting the lower part of the slot 16. To increase the size of the recess defined by the aperture 15 and the adjacent portion of the spring member 15 28, the upper part of the spring member is pushed to the left, as viewed in Figure 1, and swings about the point 19, this movement being limited by abutment with the marginal wall 18.

In Figure 2 is shown a plug conductor terminal 20 35 adapted to cooperate with the terminal post 10, and comprising a generally cylindrical portion 36 provided with an annular furrow 37 and a frusto-conical end 38. A conductor 39 may be fastened to the plug conductor terminal as 25 by swaging, indicated by the swedge indentations 40 in the frusto-conical end 38. To secure the plug conductor terminal in cooperative position with respect to the terminal post 10, the frusto-conical end 38 thereof is inserted into the aperture 15 formed in the body 12, inserting movement causing the frusto-conical end 38 to engage the marginal walls of the aperture 15 and the adjacent surface of the spring member 28, the end 38 camming the spring member 28 30 to the left, as viewed in Figure 1, and increasing the size of the recess defined by the aperture 15 and the spring member 28 to accommodate the cylindrical portion 36 of the plug conductor terminal 35. Further inserting movement causes the annular furrow 37 to be positioned adjacent the aperture 15, and the spring member 28, because of its resiliency, then snaps the annular furrow 37 into engagement with the marginal walls of the aperture 15, and holds the plug conductor terminal 35 in electrical and mechanical contact with the terminal post 10. Withdrawal movement of the plug conductor terminal 35 causes the tapering surfaces of the annular furrow 37 to again cam the spring member 28 to 40 the left, as viewed in Figure 1, to permit the passage of the generally cylindrical portion of the plug conductor terminal 35.

Referring now to Figures 4, 5, and 6, the embodiment of my invention therein disclosed comprises a terminal post 41, mounted on a base 42. The terminal post 41 is preferably formed of sheet metal bent into right angular formation, and includes a body portion 43 provided with a generally plane vertical wall 44 and a generally horizontal wall 45 extending at right angles from the lower end of the vertical wall 44. The vertical wall 44 is provided with an arcuate aperture 46, and extending substantially diagonally from a margin of the body portion 43 is a slot 47 intersecting the aperture 46.

The body portion 43 is secured to the base 42 by means of a screw 48 passing through an aperture 49 in the horizontal wall 45 and engageable with a screw-threaded aperture 50 formed in the base 42.

Biassing means are provided for cooperation with the body portion 43, and comprise an elongated generally plane leaf-spring like member 51, bent generally V-shaped to form legs 52 and 75 53 and a bight portion 54. Each leg 52 and 53

is provided with a slot 55, of a width to pass the thickness of the vertical wall 44, and of a length to extend from an adjacent end to a point short of the bight 54. To assemble the spring member 51 with the body portion 43, the vertical 5 wall 44 is inserted into the slots 55 in the legs 53 and 52 respectively, inserting movement being limited by the abutment of the leg 53 with the horizontal wall 45, and the legs 53 and 52 are predeterminedly formed so that the leg 52 will 10 normally form a chord across the arcuate aperture 46, and the end of the leg 52 will be spaced from the lower marginal wall (as viewed in Figure 4) of the slot 47. With the parts so assembled, a portion 56 is struck out from the margin 15 of the vertical wall 44 adjacent the bight 54 of the spring member 51, and the parts are thus held against unintentional displacement.

A plug conductor terminal like the terminal 35 may be inserted into the aperture 46, initial 20 movement causing the frusto-conical end to cam the leg 52 in a generally swinging movement about the bight 54, thereby increasing the size of the opening defined by the aperture 46 and leg 52 to permit the passage of the cylindrical 25 portion of the plug conductor, further inserting movement bringing the annular furrow into alignment with the aperture 46, the spring member 51 then springing back to substantially its normal position to clamp the annular furrow 30 between it and the adjacent margins of the recess 46, connection being further facilitated by reason of the fact that the margins of the slot 55 formed in the leg 52 also engage the adjacent surfaces of the annular furrow of the plug conductor terminal.

From the foregoing it will be apparent to those skilled in the art that the illustrated embodiment of my invention provides a new and improved electrical contact and connection means, 40 economical in construction and assembly, and accordingly, accomplishes at least the principal object of my invention. It further will be obvious to those skilled in the art that the illustrated embodiment of my invention may be variously 45 changed and modified without departing from the spirit of my invention, or sacrificing all of the advantages thereof, and that accordingly, the disclosure herein is illustrative only, and my invention is not limited thereto.

I claim:

1. Receptacle means for holding a conductor terminal, including a single planar wall having a base, a terminal receiving aperture formed in said wall and a slot intersecting said aperture and the base of said wall and providing a projection, biasing means insertable to a predetermined position within said slot, and an opening provided adjacent one extremity of said biasing means receiving said projection whereby to assist in holding said biasing means substantially in a plane at right angles to the plane of said wall.

2. Receptacle means for holding a conductor terminal, including a mounting, a single planar 65 wall member having a base portion located adjacent the upper surface of said mounting, said member having a terminal receiving aperture and a slot intersecting said aperture and a recess in its base portion communicating with said 70 slot, biasing means having a portion projecting through said slot and intersecting said aperture and a portion locked within said recess and engaging said mounting.

3. A mounting, receptacle means carried by 75

5 said mounting for receiving and holding a conductor terminal, comprising: a sheet metal body having a base, and an upstanding portion having a recess for receiving the conductor terminal, and also having a slot intersecting said recess and said base; leaf spring biasing means having a movable portion engageable with the conductor terminal disposed in said recess for yieldably holding the terminal in operative position, the movable portion of said biasing means being engageable with the margins of said slot to limit the movement of said portion; and the material adjacent the junction between said base and the upstanding portion of said body and the lower extremity of said biasing means being constructed and arranged to provide an interlocking connection permitting said base to rest solely upon said mounting.

4. Receptacle means for holding a conductor terminal, including a mounting, a single planar wall member having a base portion located adjacent the upper surface of said mounting, said member having a terminal receiving aperture and a slot intersecting said aperture and a recess in its base portion communicating with said slot, biasing means having a portion projecting through said slot and intersecting said aperture and a portion locked within said recess.

5. Receiving means, for holding a conductor terminal, including a wall provided with a terminal receiving aperture and a slot extending substantially longitudinally of said wall intersecting said aperture and a margin adjacent the 5 base end of said wall, means integral with said wall adjacent the intersection of said margin and said slot, leaf spring biasing means enterable through said slot with a portion intersecting said aperture, and a portion interlocking with said 10 integral means whereby to assist in holding said wall and said biasing means in assembly.

6. Receptacle means for holding a conductor terminal, including a mounting having a plane surface; biasing means in the form of a resilient member having a base resting on said surface, a recess provided in said base, and a rigid wall member engaging said surface having a terminal receiving aperture provided therein and a slot projecting inwardly from that part of the 20 wall engaging said surface whereby said wall member may be slipped over said biasing means with said biasing means being locked in said slot only when said member is secured to said 25 mounting.

HARRY A. DOUGLAS.
